[57]

ABSTRACT

An electron gun device for color television picture tubes. The electron gun has three cathodes and a plurality of grids. Means are provided for equalizing the cutoff voltages of the cathodes by equalizing the intensity of the electric field reaching the cathodes from the grids. Equalization preferably is obtained by making one or more of the apertures in the first and second grids of a diameter different from that of the other apertures, or by making the distances of one or more of the cathodes from the grids different from the corresponding distances of the other cathodes, or by a combination of both of these arrangements.

ELECTRON GUN DEVICE FOR COLOR TUBE

This invention relates to an electron gun device, and particularly to an electron gun device for a single-gun, plural-beam type of color television picture tube.

In certain prior color picture tubes having multiple cathodes, the cutoff voltages of the cathodes are not equal to one another. The result of this imbalance is that the gamma characteristics of the three colors in the picture produced by the tube are different and the colors are not natural.

In view of the foregoing, a major object of this invention is to provide a plural-cathode electron gun device whose cathodes have the same cutoff voltages. A further object of the invention is to provide a relatively simple and inexpensive means for equalizing the cutoff voltages of such cathodes.

In accordance with the present invention, the foregoing objects are met by the provision of means for equalizing the cathode cutoff voltages by equalizing the intensity of the electric field reaching the cathodes from the grids of the electron gun. The equalization means selectively limits the amount of flux reaching one or more of the cathodes. In the preferred embodiment of the invention, equalization is accomplished by making one or more of the apertures in the first and second grids of a diameter different from that of the other apertures, or by making the distances of one or more of the cathodes from the grids different from the corresponding distances of the other cathodes, or by a combination of both of these arrangements.

Further objects and advantages of the invention will be pointed out or made apparent in the following description and drawings.

In the drawings:

FIG. 1 shows a typical color television picture tube in which the electron gun of this invention can be used;

FIG. 2 is an enlarged, broken-away partially schematic view of a portion of the electron gun shown in FIG. 1;

FIGS. 3A, 3B, 4A, 4B and 4C are views similar to that of FIG. 2, each showing a different embodiment of the invention;

FIG. 5 is an enlarged detailed view of the preferred embodiment of the invention; and

FIG. 6 is a graph illustrating certain performance characteristics of the electron gun of the present invention.

FIG. 1 of the drawings shows a single-gun, plural-beam color picture tube 10 which is described in detail in U. S. Pat. application Ser. No. 697,414, filed on Jan. 12, 1968, and assigned to the same assignee as this application. The color picture tube 10, which is known by the name "Trinitron," includes a glass envelope 11 (indicated in broken lines) having a neck 12 and cone 13 extending from the neck to a color screen S provided with the usual arrays of color phosphors S_R, S_G, and S_B and with an apertured beam-selecting grid or shadow mask G_P. Disposed within the neck 12 is an electron gun A having cathodes K_R, K_G, and K_B, each of which is a beam-generating source with its thermal electron-emitting surface disposed as shown in a plane which is substantially perpendicular to the longitudinal axis of the electron gun A. In the embodiment shown, the beam-generating surfaces are arranged in a straight line so that the respective beams B_R, B_G and B_B emitted therefrom are directed in substantially horizontal

planes, with the alignment of the central beam B_G being coincident with the axis of the gun.

A first grid G₁ is spaced from the beam-generating surfaces of cathodes K_R, K_G and K_B and has apertures g_{1R}, g_{1G}, and g_{1B} formed therein in alignment with the respective cathode beam-generating surfaces. A common grid G₂ is spaced from the first grid G₁ and has apertures g_{2R}, g_{2G} and g_{2B} formed therein in alignment with the respective apertures of the first grid G₁. Successively arranged in the axial direction away from the common grid G₂ are open-ended, tubular grids or electrodes G₃, G₄ and G₅, respectively, with cathodes K_R, K_G and K_B, grids G₁ and G₂, and electrodes G₃, G₄ and G₅ being maintained in the assembled positions shown in the drawings by means of suitable non-illustrated support means of an insulating material.

For operation of the electron gun A of FIG. 1, appropriate voltages are applied to the grids G₁ and G₂ and to the electrodes G₃, G₄ and G₅. Thus, for example, a voltage of 0 to minus 400V is applied to the grid G₁, a voltage of 0 to 500V is applied to the grid G₂, a voltage of 13 to 20KV is applied to the electrodes G₃ and G₅, and a voltage of 0 to 400V is applied to the electrode G₄, with all of these voltages being based upon the cathode voltage as a reference. As a result, the voltage distributions between the respective electrodes and cathodes, and the respective lengths and diameters thereof, may be substantially identical with those of a unipotential-single beam type of electron gun which has a single cathode and first and second single-apertured grids.

With the applied voltage distribution as described hereinabove, an electron lens field will be established between grid G₂ and the electrode G₃ to form an auxiliary lens L' as indicated in dashed lines, and an electron lens field will be established around the axis of electrode G₄, by the electrodes G₃, G₄ and G₅, to form a main lens L, again as indicated in dashed lines. In a typical use of electron gun A, bias voltages of 100 V are applied to the cathodes K_R, K_G and K_B, and bias voltages of 0V, 300V, 20KV, 200V and 20KV may be applied, respectively, to the first and second grids G₁ and G₂, and the electrodes G₃, G₄ and G₅.

Further included in the electron gun A of FIG. 1 are electron beam convergence deflecting means F which comprise shielding plates P and P' disposed in the depicted spaced relationship at opposite sides of the gun axis, and axially extending deflector plates Q and Q' which are disposed, as shown, in outwardly-spaced, opposed relationship to shielding plates P and P', respectively. Although depicted as substantially straight, it is to be understood that the deflector plates Q and Q' may, alternatively, be somewhat curved or outwardly bowed, as is well known in the art.

The shielding plates P and P' are equally charged and disposed so that the central electron beam B_G will pass substantially undeflected between the shielding plates P and P', while the deflector plates Q and Q' have negative charges with respect to the plates P and P' so that respective electron beams B_B and B_R will be convergently deflected as shown by the respective passages thereof between the plates P' and Q'. More specifically, a voltage V_P which is equal to the voltage applied to the electrode G₅, may be applied to both shielding plates P and P', and a voltage V_Q, which is some 200 to 300V lower than the voltage V_P, is applied to the respective deflector plates Q and Q' to result in the respective shielding plates P and P' being at the same po-

tential, and to result in the application of a deflecting voltage difference or convergence deflecting voltages V_c between the respective plates P' and Q' and P and Q and it is, of course, this convergence deflecting voltage V_c which will impart the requisite convergent deflection to the respective electron beams B_B and B_R .

In operation, the respective electron beams B_R , B_G and B_B which emanate from the beam generating surfaces of the cathodes K_R , K_G and K_B will pass through the respective grid apertures g_{1R} , g_{1G} and g_{1B} , to be intensity modulated with what may be termed the "red," "green" and "blue" intensity modulation signals applied between the said cathodes and the first grid G_1 . The respective electron beams will then pass through the common auxiliary lens L' to cross each other at the center of the main lens L. Thereafter, the central electron beam B_G will pass substantially undeflected between shielding plates P and P' since the latter are at the same potential. Passage of the electron beam B_B between the plates P' and Q' and of the electron beam B_R between the plates P and Q will, however, result in the convergent deflections thereof as a result of the convergence deflecting voltage V_q applied therebetween, and the system of FIG. 1 is so arranged that the electron beams B_B , B_G and B_R will desirably converge or cross each other at a common spot centered in an aperture between adjacent grid wires g_P of the beam selecting grid or mask G_P so as to diverge therefrom to strike the respective color phosphors of a corresponding array thereof on screen S. More specifically, it may be noted that the color phosphor screen S is composed of a large plurality of sets or arrays of vertically extending "red," "green" and "blue" phosphor stripes or dots S_R , S_G and S_B with each of the arrays or sets of color phosphors forming a color picture element as in a chromatron type color picture tube. Thus, it will be understood that the common spot of beam convergence corresponds to one of the thusly formed color picture elements.

The voltage V_P may also be applied to the lens electrodes G_3 and G_5 and to the screen S as an anode voltage in conventional manner through a non-illustrated graphite layer which is provided on the inner surface of cone 13 of the tube envelope. The grid wires of screen grid G_P may have a post-focusing voltage V_M ranging, for example, from 6 to 7KV applied thereto as indicated.

To summarize the operation of the depicted color picture tube of FIG. 1, the respective electron beams B_B , B_G and B_R will be converged at screen grid G_P and will diverge therefrom in such manner that electron beam B_B will strike the "blue" phosphor S_B , electron beam B_G will strike the "green" phosphor S_G and electron beam B_R will strike the "red" phosphor S_R of the array or set corresponding to the grid aperture at which the beams converge. Electron beam scanning of the face of the color phosphor screen is effected in conventional manner, for example, by horizontal and vertical deflection yoke means indicated in broken lines at D and which receives horizontal and vertical sweep signals whereby a color picture will be provided on the color screen. Since, with this arrangement, the respective electron beams are each passed, for focusing, through the center of the main lens L of the electron gun A, the beam spots formed by impingement of the beams on the color phosphor screen S will be substantially free from the effects of coma and/or astigmatism

of the said main lens, whereby improved color picture resolution will be provided.

FIG. 2, which is an enlarged view of the cathode region of the tube 10 shown in FIG. 1, shows thermal electron emitting surfaces 14, 15 and 16 of three cathodes K_R , K_G and K_B which are arranged in a plane 21 which is perpendicular to the longitudinal axis of the tube. The first grid G_1 is arranged in a similarly perpendicular plane 22 which is located at a distance D_1 from the plane 21. The three circular apertures g_{1R} , g_{1G} and g_{1B} of grid G_1 have equal diameters ϕ_{1R} , ϕ_{1G} , and ϕ_{1B} . The second grid G_2 is arranged in another similarly perpendicular plane 23 which is located at a distance D_2 from the plane 22. The three apertures g_{2R} , g_{2G} and g_{2B} of grid G_2 have equal diameters ϕ_{2R} , ϕ_{2G} and ϕ_{2B} .

Applicants have discovered that when a high voltage is applied to the third grid G_3 , the intensity of the electric field reaching the center cathode K_G is greater than the intensity of the electric field reaching the other cathodes on both sides, and that the cutoff voltage (absolute value) of the cathode K_G is greater than the cutoff voltages of the other cathodes K_B and K_R . This difference in cutoff voltages causes the problems set forth hereinabove. That is, although the video signal voltages applied to the cathodes K_R , K_G and K_B may be selected to have the same voltages to produce a white picture, because of the cutoff voltage imbalance, the video signal voltages must be changed with respect to each other according to the differences in their cutoff voltages.

Two arrangements are shown in FIGS. 3A and 3B for providing the same cutoff characteristics for the cathodes K_R , K_G and K_B .

The arrangement shown in FIG. 3A, the electric field reaching the cathode K_G through the aperture g_{1G} is reduced by selecting the diameter ϕ_{1G} of the central aperture g_{1G} in the first grid G_1 to be smaller than the diameters ϕ_{1B} and ϕ_{1R} of the other apertures g_{1B} and g_{1R} in the first grid.

The arrangement of FIG. 3B is like that of FIG. 3A except that the diameter ϕ_{2G} of the central aperture g_{2G} of the second grid G_2 also is smaller than the diameter of its neighboring apertures.

Other arrangements for the same purpose are shown in FIGS. 4A, 4B and 4C. In each of these arrangements, the diameters of the apertures in grids G_1 and G_2 are uniform, but the distances D_1 and/or D_2 relating to the central electron beam (green) is made greater than the corresponding distances for the other electron beams (blue and red) in order to equalize the intensity of the electric field reaching each cathode.

In the FIG. 4A arrangement, the intensity of the electric field reaching the central cathode K_G is reduced by locating the beam-emitting surface 15 of that cathode farther away from grids G_1 and G_2 than the other cathodes by a distance D'_1 . Of course, this has the effect of locating cathode K_G at a greater distance from the control electrode G_3 .

In the FIG. 4B arrangement, the same effect is achieved by bending the metal plate forming grid G_2 away from grid G_1 by a distance D'_2 in the vicinity of the central aperture g_{2G} .

In the FIG. 4C arrangement, the structural features shown in FIGS. 4A and 4B have been combined to give an even greater reduction in the electric field intensity at the surface 15 of cathode K_G .

FIG. 5 shows one specific example of the gun device described in the foregoing description. The material of which the grids G_1 , G_2 and G_3 are formed is stainless steel of 0.2 mm. thickness. Other dimensions and the voltages applied to the grids are shown in FIG. 5. It can be seen that the FIG. 3A arrangement is used in the FIG. 5 structure; that is, the diameter ϕ_{1G} is 0.77 mm, and ϕ_{2G} is greater, 0.8 mm.

FIG. 6 shows experimentally observed relationships between various voltages observed in the structure shown in FIG. 5. In FIG. 6:

E_{C0} is the cutoff voltage between the cathode K and the first grid G_1 ; that is, the negative voltage necessary to be applied to G_1 to cause cathode cutoff;

E_{C2} is the voltage applied to the second grid G_2 . The cutoff characteristics of the side beams are shown as line A in FIG. 6. Line B represents the cutoff characteristic of a structure like the FIG. 5 structure except that both ϕ_{1G} and ϕ_{2G} are equal to 0.8 mm; that is, a structure in which the diameters of the center apertures of the first and second grids G_1 and G_2 are equal to diameters of the corresponding side apertures. It is seen from FIG. 6 that there is a difference of about eight volts between the cutoff characteristic curves A and B throughout the section labeled "operating range."

In the gun device actually shown in FIG. 5; that is, one having a center aperture of the first grid G_1 whose diameter ϕ_{1G} is smaller than the diameter of its neighboring apertures, the cutoff characteristics of the center beam are shown as Line C. The differences between the cutoff voltages of the center beam and the side beams are so small as to be negligible in the "operation range." Thus, the problem of differing cathode cutoff voltages has been solved.

In each of the embodiments of this invention, the relative reduction in the diameter of the aperature g_{1G} and/or the aperture g_{2G} (FIGS. 3A and 3B), or the increase of the distance from the beam generating surface 15 of the central cathode K_G to the portion of grid G_1 having the corresponding aperture g_{1G} and/or to the portion of the grid G_2 having the corresponding aperture g_{2G} , serves to relatively decrease the angle of the cone that can be projected from the peripheries of the apertures to the center of the beam generating surface 15. Thus, although the electric field constituting the auxiliary lens L' (FIG. 1) is most intense at the axis of the gun, the effect of that field at surface 15 of central cathode K_G is minimized so as to be equalized with the

effect of the field at surfaces 14 and 16 of side cathodes K_S and K_R .

The above description of the invention is intended to be illustrative and not limiting. Various changes or modifications in the embodiments described may occur to those skilled in the art and these can be made without departing from the spirit or scope of the invention as set forth in the claims.

We claim:

1. An electron gun device for a color picture tube comprising two side cathodes and a central cathode therebetween having beam generating surfaces arranged substantially in a row for emitting electrons generally in parallel directions, first and second grids spaced successively in the axial direction away from said beam generating surfaces and having apertures respectively aligned with the beam generating surfaces and through which the emitted electrons are collimated into respective electron beams, and a plurality of electrodes maintained at different potentials and arranged axially following said second grid to provide an electric field defining a main lens means by which said beams are focused and cooperating with said second grid to provide another electric field defining an auxiliary lens means by which the beams from said side cathodes are converged with respect to the beam from said central cathode for passage of all of the beams through the center of said main lens means, the angle of a cone that can be projected to the center of said beam generating surface of said central cathode from the peripheries of the respective aligned apertures of said grids being smaller than the angles of the corresponding cones for said side cathodes for equalizing the effects of said other electric field at said beam generating surfaces of said cathodes so that the latter will have equal cutoff voltages.

2. An electron gun according to claim 1, in which at least one of the apertures of said first and second grids which are aligned with said central cathode is of a size smaller than the sizes of the apertures of said grid aligned with said side cathodes.

3. An electron gun according to claim 1, in which said beam generating surface of the central cathode is at a distance from the aligned aperture in at least one of said first and second grids that is greater than the distance from the beam generating surfaces of said side cathodes to the corresponding apertures of the grids.
